Fig. 2

UNITED STATES PATENT OFFICE

WILLIAM C. ROE, OF PITTSBURGH, PENNSYLVANIA

PHONOGRAPH STOP

Application filed December 17, 1927. Serial No. 240,773.

This invention relates to improvements in phonographs and more particularly to an automatic stop mechanism for the same.

One of the objects of my invention is to provide an improved automatic stop mechanism for phonographs which cooperates with a brake to automatically apply the brake to stop the phonograph after the end sound groove on a record is reached by the stylus.

10 Still another object of my invention is to provide an automatic brake mechanism which may be attached to any of the present standard talking machines without materially altering the same.

15 Another object of my invention resides in the provision of an improved phonograph stop mechanism which may be pre-set independent of the tone arm, and which when in pre-set position will not interfere with the 20 playing of the phonograph, but when restored therefrom will effect stopping of the phonograph.

Another object of my invention is to provide an improved automatic stop for phonographs which will be durable in construction, simple and positive in operation, and economical to manufacture.

These and other objects of my invention and the invention itself will be apparent 30 from reference to the following description of certain embodiments thereof, and in which description reference will be had to the accompanying drawings forming a part of this specification.

35 Referring to the drawings:

Fig. 1 is a top plan view of a fragment of a phonograph embodying a preferred form of my invention, in braking position;

40 Fig. 2 is a similar view of the foregoing embodiment, in non-braking position;

Fig. 3 is a vertical sectional view of the foregoing embodiment, some of the parts being shown in elevation.

45 Referring now to Figures 1 to 3, inclusive, wherein like parts are designated by like reference characters, at 1, I show a fragment of the top of a phonograph cabinet, at 3, a disc record supporting turntable, supported on a motor driven spindle 2, having a down-turned peripheral flange 4. A tone arm 7,

supporting a sound-box 8, having a reproducing stylus needle 9 is pivoted to swing in a vertical plane on the cabinet above the turntable and disk.

A base plate 21, secured by screws 22 to the 55 cabinet below the turntable and adjacent the periphery thereof supports the mechanism. An internally threaded aperture 23 is provided in the plate 21 into which the reduced threaded portion 25 of a post 24 is threaded. An internally threaded bore 26 at the upper 60 end of the post 24 is adapted to receive a machine screw 27 to retain a cap 28 on the upper end of a hollow outer sleeve 29. A hollow block 30 is rotatably mounted on the post 24 65 adjacent its lower end within an inner hollow sleeve 31 telescoped within the hollow outer sleeve 29, said block and sleeves being disposed in co-axial alignment with the post 24. A spiral contractile spring 32 is coiled about 70 the post 24, the free ends being anchored in suitable apertures in the cap and block. Tension upon the spring 32 is adjusted by loosening the screw 27 and turning the cap 28 by means of its polygonal upper flange. The 75 outer sleeve is held against rotation on the inner sleeve by virtue of a set screw 33 screwed into the threaded opening 34 in the outer sleeve against the inner sleeve outer periphery, which screw may also permit relative adjusting of the inner and outer sleeves.

The outer sleeve is reduced at 35 to receive the hub of an arcuate pointer 36 placed and secured by turning the reduced end portion 80 of the sleeve over the edges of the aperture 37 in the arm. The pointer 36 is provided with a reinforcing rib 38 and a handle 39 and is adapted to extend over the turntable and disk record and of sufficient length to be contacted with the needle 9 when the same has reached the innermost groove in the record. The end of the arm may be formed with an inclined portion 40 adapted 85 to be engaged by the needle to apply the brake in a manner which will hereinafter be described. The arcuate form of the pointer permits it to lie closely to the rim of the turntable when in normal position.

A plate 41 having a curved edge 45 and a relatively straight edge 20, is carried by 100

the block 30 and held under tension by the coiled spring 32 and is adapted to support a ratchet wheel 42 adjacent a central portion thereof, said ratchet wheel being rotatable on a vertical axis on a pin 43 threaded into a threaded aperture in the plate 41. The end of the plate 41 is pierced and threaded at 46 to receive a screw 47 for pivotally supporting a bell crank ratchet lever 48. Said lever is provided with a hooked arm 49 and a relatively short arm 50. At 80 I show a pad which protects the record against accidental damage by the arm 36. An inertia weight element 51, having a downturned tongue 6 is pivoted separately on the screw 47 for a purpose later set forth.

An upstanding projection 53 is provided on the plate 45 to provide a stop to limit the movement of the ratchet tooth of the arm 49. The short arm 50 of the ratchet tooth lever 48 is disposed between an arm 54 secured at 55 to the inner sleeve 31 and a flat spring 56 disposed to one side of the arm 54.

An upstanding apertured projection 57 is provided on one side of the plate 45 into which a set screw 58 is screwed to retain the arm 54 in certain adjusted positions. The arms 36 and 54 and the plate 45 and its associated parts are adapted to swing in unison 30 on the post 24, from a braking position to a non-braking position which will hereinafter be more fully described.

Secured by screws 60 and 61 to the base plate 21 is a gear element 62 which is substantially semi-circular and provided with gear teeth 63 meshed with the teeth of a pinion 64 secured to and above the ratchet wheel 42 and journaled for rotation on the pin 43. One extremity of the plate 21 is provided with an aperture 65 into which a machine screw is disposed to pivotally support a bell crank lever 66 carrying a brake shoe 67 at one end and a friction block 68 on the lever portion 69 for contact by the 45 curved face 45 of the plate 41.

To condition the stop mechanism for operation, the pointer 36 is swung on its pivot into "set" position shown in Fig. 2, carrying with it the plate 45 and its associated parts 50 and also the arm 54 with the detent arm 49 making ratcheting engagement with the ratchet wheel 42 to prevent a return of the mechanism. The brake arm 66 pivoted at 65 is provided with a shoe 67, normally resting upon the inner surface 70 of the flange 4. The dotted arcuate line 71 indicates the course traversed by the pointer 36 when set for the automatic braking operation. The dotted arcuate line 72 indicates the course 55 of the stylus needle relatively to the rotatable record, and as the needle is moving toward the innermost groove on the record towards the inclined end of the pointer 36. When the needle 9 reaches a point 73 which 60 is the point of intersection between the lines

71 and 72 it has engaged the inclined end of the pointer 36 and shifts the same slightly to the left, this slight movement causing the arm 54 to engage with the short arm 50 of the ratchet lever and move the ratchet arm 49 out of engagement with the ratchet teeth of the gear wheel 42. The spring 32 causes the pointer to return to normal position shown in Fig. 1, the pinion 64 rotating on the gear segment 62 until the curved face 45 of the plate 41 engages the friction block 68 of the bell crank brake lever to cause it to press the brake shoe 67 firmly against the inner periphery of the flange 4, the friction between the same causing the turntable to stop.

The inertia of the weight 51 exerted against the ratchet 49 by the tongue 6 overcomes the tendency of the ratchet lever to reengage the teeth of the ratchet wheel 42 until the ratchet wheel has ceased to move by virtue of the cessation of movement of the plate 41, at the end of the stroke.

Having thus described my invention in a specific embodiment I am aware that numerous and extensive departures may be made from the embodiment herein illustrated and described but without departing from the spirit of my invention.

I claim:

1. In combination with a phonograph of the type employing disc records, a turntable, a reproducer element adapted to traverse a record placed on the turntable, a pointer journaled laterally of the phonograph turntable and adapted to be swung over the upper surface of the supported record in a direction opposite to the direction of travel of the reproducer, a portion thereof adapted to be "set" in the path of the reproducer element at the end of the record thereon, a spring constantly exerting an effort to restore the pointer to its normal position; a ratchet mechanism adapted to retain the pointer in the path of the reproducer and means actuatable by a slight pressure contact of the reproducer element against the pointer to trip the ratchet mechanism whereby said spring will return the pointer to a normal position lateral of the record.

2. In a phonograph mechanism, a "stop" therefor comprising a turntable and brake therefor, and a pointer movable from a normal position lateral of the record over the record in a direction opposite to the direction of travel of the reproducer to any of a plurality of adjusted "set" positions corresponding to the radially disposed position of the innermost groove of the record, means to retain the pointer in such adjusted position, and means actuatable by a slight pressure contact of the reproducer element against the pointer to restore the pointer and to actuate the brake.

3. In an automatic stop for mechanisms,

the combination with a shiftable pointer manually rotatable in one direction to a given predetermined "set" position, in the path of a movable part of the mechanism, a spring normally biasing it towards an opposite normal position, an element rotatable with the pointer, relatively fixed means disposed adjacent the rotary element and engageable therewith during a range of "set" positions thereof, said element normally rotatable by virtue of the engagement of said rotary element and said fixed means, a latch to prevent relative rotary movement of the element and the said means, to lock the "set" element in a set position relative to the fixed element, a trigger movable upon slight movement of the pointer caused by impact therewith by the mechanism part to trip the latch, said spring being operative to thereupon release the pointer, and inertia means adapted to hold the latch inoperative during restoring movement of the set element.

4. In an automatic stop mechanism for phonographs, the combination with a phonograph turntable, a swivable pointer normally biased toward a normal position and adapted to be rotated over the face of the turntable and the record carried thereby to a "set" position, a support for said pointer, a plate below the turntable rotatable with the pointer, an arm secured to the pointer and movable therewith adjacent said plate, a pinion, and a toothed element in driving engagement therewith, said toothed element carried by said support with its teeth disposed concentrically of the pointer axis, a ratchet carried by said pinion, a ratchet detent engageable with the ratchet, said arm engageable with the detent upon an initial movement of the pointer from a "set" position toward its normal position to move it from engagement with the pinion element, said detent being normally biased toward pinion engaging position, and an inertia element operative responsive to the return movement of the plate toward normal position to hold the detent out of engagement with the pinion, and means operated responsive to the return movement of said plate to stop the phonograph.

5. In a phonograph comprising a rotatable record support, a stop mechanism therefor comprising an index arm movable from a normal position laterally of the support over the record, a spring tending to return the index arm to normal position, a ratchet adapted to retain the index arm in its "set" position in opposition to the spring, a trigger for tripping the ratchet, actuated by a slight pressure contact of a phonograph tone arm supported part against the index arm in traversing the record to operate the trigger, and means effective upon a tripped return movement of the index arm, adapted to discontinue rotation of the record.

6. In a phonograph comprising a rotatable record support, a stop mechanism therefor comprising an index arm movable from a normal position laterally of the support over the record to effect rotation of the support, a spring tending to return the index arm to normal position, a ratchet adapted to retain the index arm in its "set" position in opposition to the spring, a trigger for tripping the ratchet, actuated by a slight pressure contact of a phonograph tone arm supported part against the index arm in traversing the record to operate the trigger, and means effective upon a tripped return movement of the index arm, adapted to discontinue rotation of the record.

7. In a phonograph comprising a rotatable record support, a stop mechanism therefor comprising an index arm movable from a normal position laterally of the support over the record, a spring tending to return the index arm to normal position, a ratchet adapted to retain the index arm in its "set" position in opposition to the spring, a trigger for tripping the ratchet, actuated by a slight pressure contact of a phonograph tone arm supported part against the index arm in traversing the record to operate the trigger, and means effective upon a tripped return movement of the index arm, adapted to discontinue rotation of the record, and inertia means responsive to the restoring of the index arm adapted to continue the ratchet in disabled position to which it is tripped, during the return movement of the arm.

8. In a phonograph comprising a rotatable record support, a stop mechanism therefor comprising an index arm movable from a normal position laterally of the support over the record to effect rotation of the support, a spring tending to return the index arm to normal position, a ratchet adapted to retain the index arm in its "set" position in opposition to the spring, a trigger for tripping the ratchet, actuated by a slight pressure contact of a phonograph tone arm supported part against the index arm in traversing the record to operate the trigger, and means effective upon a tripped return movement of the index arm, adapted to discontinue rotation of the record, and means comprising said spring and a weight adapted by inertia to effect complete return of the index arm after tripping thereof, to normal position.

9. In a phonograph comprising a rotatable record support, a stop mechanism therefor comprising an index arm movable from a normal position laterally of the support over the record to effect rotation of the support, a spring tending to return the index arm to normal position, a ratchet adapted to retain the index arm in its "set" position in opposition to the spring, a trigger for tripping the ratchet, a weak spring normally retracting the trigger, said trigger actuated by a slight

- pressure contact of a phonograph tone arm supported part against the index arm in traversing the record to operate the trigger, and brake means effective upon a tripped return movement of the index arm, adapted to discontinue rotation of the record, and means comprising said spring and a weight adapted by inertia to effect complete return of the index arm after tripping thereof, to normal position.
10. In a phonograph mechanism, comprising a turntable and a reproducer element movable over the turntable, a stop for said turntable, comprising a brake engageable therewith, and a pre-set pointer movable from a normal position laterally of the record, over the record to adjustably bring its pointer portion to a position adjacent to the end groove of the record, and means actuatable by a slight pressure contact of the reproducer element against the pointer, to restore the pointer and to actuate the brake.
11. In a phonograph mechanism, comprising a turntable and a reproducer element movable over the turntable, a stop for said turntable, comprising a brake engageable therewith, and a pre-set pointer movable from a normal position laterally of the record over the record to adjustably bring its pointer portion to a position adjacent to the end groove of the record, and means actuatable by a slight pressure contact of the reproducer element against the pointer, to restore the pointer and to actuate the brake, and a brush carried by the pointer, and adapted to contact with a record on the turntable.
12. In a phonograph mechanism, a "stop" therefor comprising a turntable and brake therefor, and a pointer movable from a normal position lateral of the record over the record in a direction opposite to the direction of travel of the reproducer to any of a plurality of adjusted "set" positions corresponding to the radially disposed position of the innermost groove of the record, means to retain the pointer in such adjusted position, and means actuatable by a slight pressure contact of the reproducer element against the pointer to restore the pointer and to actuate the brake, and a brush carried by the pointer, and adapted to contact with a record on the turntable.
13. In a phonograph mechanism, a turntable, motor means to rotate the turntable, a reproducer element movable over the turntable while rotating, a stop mechanism for the turntable, for discontinuing its rotation by said motor means, and a pre-set pointer movable from a normal position laterally of the record over the record to adjustably bring its pointer portion to a position relative to the record having a definite predetermined relation to a position thereon, at which it is desired to discontinue movement of the reproducer element thereover, and means re-

sponsive to the pre-set positioning of said pointer to effect actuation of said stop means when the reproducer element reaches the said predetermined position relative to the position of the pointer element.

In testimony whereof I hereunto affix my signature this 25th day of May, 1927.
